(57) **CLAIM**

The ornamental design for a headlight cover, as shown and described.

DESCRIPTION

FIG. 1 is a perspective view taken from a front, left side of a headlight cover according to our design;

FIG. 2 is a perspective view taken from a rear, left side thereof;

FIG. 3 is a front elevation view thereof;

FIG. 4 is a left side elevation view thereof;

FIG. 5 is a rear elevation view thereof;

FIG. 6 is a right side elevation view thereof;

FIG. 7 is a top plan view thereof; and,

FIG. 8 is a bottom plan view thereof.

Throughout the Figures, where shown: the dotted/dashed lines illustrate unclaimed boundaries of surfaces claimed as part of the design. The invention includes mirror images of the headlight cover shown in the Figures.
